Exhibit 'A' Consists of 4 Photographs of Commercial Bibs.

Primary Examiner—B. J. Bullock
Assistant Examiner—Celia A. Murphy

[57]

CLAIM

The ornamental design for a bib, as shown and described.

DESCRIPTION

FIG. 1 is a front elevational view of a bib embodying our new design;

FIG. 2 is a perspective view thereof;

FIG. 3 is a perspective view thereof, shown in use, the broken line showing of a baby, being for illustrative purposes only;

FIG. 4 is a front elevational view of a second embodiment of the design of FIG. 1;

FIG. 5 is a perspective view of FIG. 4;

FIG. 6 is a perspective view of FIG. 4 shown in use, the broken line showing of a baby being for illustrative purposes only;

FIG. 7 is a front elevational view of a third embodiment of the design of FIG. 1;

FIG. 8 is a perspective view of FIG. 7;

FIG. 9 is a perspective view of FIG. 7 shown in use, the broken line showing of a baby being for illustrative purposes only.
